WILLIAM J. GAGNON, OF BRIDGEPORT, CONNECTICUT, ASSIGNOR TO THE BRYANT ELECTRIC COMPANY, OF BRIDGEPORT, CONNECTICUT, A CORPORATION OF CONNECTICUT.

ELECTRICAL SWITCH.

1,079,233.

Specification of Letters Patent. Patented Nov. 18, 1913.

Application filed July 21, 1909. Serial No. 508,815.

To all whom it may concern:

Be it known that I, WILLIAM J. GAGNON, a citizen of the United States of America, residing in the city of Bridgeport, in the county of Fairfield, in the State of Connecticut, have invented certain new and useful Improvements in Electrical Switches, of which the following is a specification.

My invention relates to improvements in electrical switches, more particularly of the push button type, and my improvements are especially intended for use in pendent switches.

The main objects of my invention are to so construct the switch that with the use of a single push button, I may secure ease and certainty of motion with a snap action and to so construct the insulating casing and arrange the metallic parts therein as to provide a simple and convenient strain relief sufficient for the purposes of a pendent switch.

In the accompanying drawings Figure 1 is a side elevation of my improved pendent switch, with the metallic casing and lining in section; Fig. 2 is a plan view of the insulating body; Fig. 3 is a vertical section of the switch, on the line 3—3, Fig. 2; Fig. 4 is a vertical section on the line 4—4, Fig. 2; Fig. 5 is a perspective view of certain parts of the actuating mechanism.

I form the insulating body A in the form of a cup, inverted, that is to say, closed at the top *a*, (except for the holes for the screws) and open at the bottom, (Fig. 3), and within this cup I arrange the switch mechanism, comprising a rotary snap switch construction B in the bottom of the cup, and means for imparting intermittent rotary motion to this snap switch by means of a single push button C through the medium of a spirally grooved spindle D.

The switch B may be of any well known or convenient construction, such for example as the eccentric snap or flat escapement switch of the Hart reissued patent 11,395, Dec. 12, 1893, or the Paiste Patent No. 483,862. It will suffice to note that *b*, *b*, represent the intermittently rotating contact clips to make and break contact with the contacts *f* formed in one with the terminal posts F, which are secured in notches G in the edges of the cup A, (Figs. 1 and 4), and are provided with binding screws *f*¹ for the bared ends of the two or more suspending

and conducting wires W. On the outside of the cup, on the sides and top I form grooves *w* to receive the covered wires snugly. The lined metallic casing E, Fig. 1, is made to fit snugly over the insulating body and to confine the covered parts of the wires in these grooves, giving to the wires sharp bends around the corners *w*¹, Fig. 4, and other bends where the wires pass out through the outlet bushing *e* at the top of the casing. This confining of the covered wires in the considerable lengths of grooves along the outer sides and top of the cup-shaped insulating body, together with the corners for bends provide a friction on the wires ample sufficient to relieve the connections of the wire ends at the binding or terminal posts from any strain due to the weight or handling of the pendent switch.

To actuate the rotary snap switch I prefer to employ the following means:—On the lower end of the spindle *b*¹ of the switch I secure a crown piece II, Fig. 5, with radial teeth *h* and upwardly bent teeth *h*¹. These latter serve the purpose of providing a number of abutments against any of which the end of the spring *b*² of the switch may engage, as adjustment of the spring may require. The radial teeth *h* serve as ratchet teeth against which engage the teeth *p*, *p*, on the pawl plate P, secured to the upper end of the rotary spindle D. This spindle may be hollow to receive the upper end of a spiral spring S (Fig. 4) which resting at its lower end in the cupped bottom of the push button C, tends at all times to keep the pawl P pressed into engagement with the crown ratchet plate II. The push button or rod C is guided in a bent cross bar K secured by screws *k* (Fig. 3) across the mouth of the inverted cup A. The upper end of the push button is formed with lugs *c*, *c*, which are notched or bifurcated, Fig. 5, to engage vertical guides *h*¹, *h*¹, on the upper side of the cross bar K, thereby preventing the push button from turning.

On the exterior of the spindle D is formed a spiral groove *d* and on the interior of the hollow push button C is a projection, preferably in the form of a spiral rib *c*¹, Fig. 5, to engage the spiral groove *d*, so that the longitudinal motion of the push button (it is indicated in mid position in Fig. 3) will be converted into a rotary motion of the spindle D, and through the pawl and ratchet
